UNITED STATES PATENT OFFICE

FREDERICK E. ROTHE, OF WENTZVILLE, MISSOURI

BARBER CHAIR

Application filed December 23, 1929. Serial No. 416,081.

This invention relates to barber chairs, and an object of the invention is to provide a barber chair with plural back cushions, both of which are adapted to fold within the back frame while the barber operates upon full grown persons, and to further provide for extending one of the backs for use as a seat while the barber is serving a child or other small person.

10 Further objects of the invention are to provide, in a manner as hereinafter set forth, a barber chair of the character referred to that is strong, compact and durable, thoroughly reliable for its intended purpose, presenting 15 a very pleasing appearance, very simple in its method of assembly, and simple to operate, and comparatively inexpensive to manufacture.

With the foregoing and other objects in 20 view, the invention consists of a novel construction, combination, and arrangement of parts, as will be hereinafter more specifically described and illustrated in the accompanying drawings, wherein is disclosed an embodiment of the invention, but it is to be understood that changes in the variations, and modifications, may be resorted to without departing from the spirit of the claim herein appended.

25 In the drawings:—wherein like reference characters denote corresponding parts throughout the several views:—

Figure 1 is a fragmentary side elevation of a barber chair formed in accordance with 30 the present invention,

Fig. 2 is a front elevation thereof showing the outer back extended,

Fig. 3 is a horizontal section through the back of the chair, with the outer cushion extended and the outer cushion being in top plan with a portion thereof broken away, and

Fig. 4 is a vertical section in detail through the back frame illustrating the outer and inner cushion in folded relation.

45 Referring to the drawings in detail, the

barber chair is formed of a conventional seat 5, supported on a pedestal 6 that rests upon the floor. A pair of arms 7 are supported on the seat 5, one on each side thereof.

Pivots supported at its lower end as at 50 8 is the back frame indicated generally at 9. The frame 9 is formed with a solid back wall 10, and open front, inwardly directed side walls 11, 12, secured at their rear ends to the solid back 9. The frame 9 further includes 55 an inwardly directed top wall 13 secured to the rear wall 10.

The frame 9 forms an open front casing in which is seated, within the folded position, an inner cushion indicated generally at 14 60 and a double faced outer cushion indicated generally at 15.

The inner cushion 14 is resiliently mounted within the wall of the frame, so as to be retractile therein, on a plurality of spaced coil 65 springs 16 and the length of the coil springs when not under tension, are such as to force the rear cushion 14 to the position shown in Fig. 3 of the drawings.

The outer ends of the coil springs 16 are 70 anchored in a suitable manner to the inner face of the inner cushion 14, while the inner ends of the coil spring 16 are anchored to the rear wall 10 of the casing.

The double-faced outer cushion 15 is 75 formed of a substantially rectangular frame 17, formed with inwardly projecting lugs 18 that are pivoted to the lower portions of the side walls 11, 12 on pins 19. A solid bridge wall or partition wall 20 is secured between 80 the edges of the frame 17 and forms a division between the outer face 21 and the inner face 22 of the face 15.

Secured to the inner face of the partition 85 20 is a transversely disposed, bar 23 of C-shaped cross section. The cross section of the bar 23 forms an interior channel in the bar, and this channel is restricted by the relatively narrow slots 24 that communicate 90 with the channel.

The bar 23 is secured to the inner face of the partition wall 20 by any suitable means. A pair of flat bars 25, 26 that form supporting arms for the outer cushion 15 are slidably mounted in the outer portions of the channel bar 23. In the folded positions, both arms 25, 26 retract within the channel bars 23, so as to permit the folding of the inner cushion 15 from the position shown in Fig. 3, to that shown in Fig. 4 of the drawings.

On the inner adjacent ends of the arms 25, 26 are a pair of projecting lugs 27, 28 that extend through the relatively narrow slot 24 of the bars. A pair of links 29, 30 of angular configuration, are pivoted at their vertices as at 31, 32 to the rear portion of the partition 20 on the inner face thereof.

On the free end of adjacent legs of each link 29, 30, are formed elongated slots 33 that movably couple the links to the projecting pins 27, 28 that are seated therein. On the free ends of the other legs of each link 29, 30 are formed outstanding lugs 34.

A similar pair of lugs 35 are formed on the face of the partition wall 20 adjacent the forward margin thereof. The opposite ends of a pair of helical coil springs 36, 37 are supported by and between the lugs 34 on the links and the lugs 35 on the partition wall.

The springs 36, 37 normally urge the arms 25, 26 outwardly into the position shown in Fig. 3 of the drawings, and when the arms 25, 26 are retracted within the channel bar 23, the links 29, 30 will compress the springs.

To fold the outer cushion 15 from the position shown in Figs. 1, 2 and 3 to the position shown in Fig. 4 of the drawings, the arms 25, 26 are pushed inwardly by the hand of the operator until their edges permit the frame 17 to be folded within the back frame 9, whereupon the outer double-faced cushion 15 will act as a back rest for a normal sized person.

When the outer cushion 15 is extended to rest upon the arm 7 of the chair, the arms 25, 26 will be urged outwardly by action of springs 37, 36 to rest upon the arms 7. The inner cushion 14 will then expand to the position shown in Fig. 3 of the drawings, to serve as a back rest for a child, while the outer cushion 15 will form the seat.

It is to be understood that by describing in detail, herein any particular form, structure or arrangement, it is not intended to limit the invention beyond the terms of the claim, or the claims of the prior art.

Having thus described my invention, what I claim as new is:

10 A back for barber chairs comprising a back frame including an open front, a back wall, and side walls extending from the back wall, an inner cushion disposed within the frame and retractile with respect thereto, an outer 65 cushion pivotally connected to the back

frame, a channel bar extending transversely of and disposed in the outer cushion, a pair of supporting arms slidable in the channel bar, and retractile means for extending the arms beyond the sides of the outer cushion for engagement with the arms of a chair for supporting the outer cushions when extended from the back frame, and said means including an angular link for each supporting arm, and a compressible spring associated with the arm.

In testimony whereof I affix my signature.

FREDERICK E. ROTHE.
